TRAY

Vaughn A. Foster, Gaston, Ind.

Application April 24, 1952, Serial No. 19,455

Term of patent 14 years

(Cl. D44—10)

To all whom it may concern:

Be it known that I, Vaughn A. Foster, a citizen of the United States and a resident of Gaston, in the county of Delaware, State of Indiana, have invented a new, original, and ornamental Design for a Tray, of which the following is a specification, reference being had to the accompanying drawing, forming a part hereof:

Fig. 1 is a top plan view of a tray showing my new design.

Fig. 2 is a vertical longitudinal sectional view, on broken line 2—2 in the direction of arrow 2 in Fig. 1.

Fig. 3 is a vertical cross section view on broken line 3—3 in the direction of arrow 3 in Fig. 1;

Fig. 4 is a vertical cross sectional view on broken line 4—4 in the direction of arrow 4 in Fig. 1.

Fig. 5 is a side elevational view thereof.

I claim:

The ornamental design for a tray, as shown.

VAUGHN A. FOSTER.
